UNITED STATES PATENT OFFICE.

LOUIS N. BRUNER, OF NEW YORK, AND SIMON D. OLSEN, OF BROOKLYN, NEW YORK.

GLASS-TUBE SPINNING AND DRAWING APPARATUS.

Application filed June 9, 1920. Serial No. 387,638.

To all whom it may concern:

Be it known that we, LOUIS N. BRUNER, a citizen of the United States, residing at New York city, in the county of New York and State of New York, and SIMON D. OLSEN, a subject of the King of Norway, residing at Brooklyn, in the county of Kings and State of New York, have invented certain new and useful Improvements in Glass-
10 Tube Spinning and Drawing Apparatus, of which the following is a specification.

This invention relates to apparatus and processes for making glass tubes, and has for its object to provide an improved apparatus and process whereby glass tubes of uniform bore may be easily and quickly made by machine without requiring skilled labor.

Other objects of the invention will appear as the description proceeds; and while herein minute details of the invention are described, the invention is not limited to these, since many and various changes may be made without departing from the scope of the invention as claimed.

In the accompanying drawing, showing by way of example one of many possible embodiments of the invention,

Figure 1 is a vertical central sectional view of the apparatus;

Fig. 2 is a front elevation of the same;

Figs. 3 and 4 are fragmental vertical central sectional views showing steps in the earlier stages of the process, and

Fig. 5 is fragmental front elevation showing a step in the final stages of the process.

Our improved apparatus is shown mounted on a base 10 carrying thereon a standard 11 comprising a base web 12, side flanges 13, and a front web 14, the latter provided with upper and lower bearing brackets 16 and 17 having upper and lower aligned openings.

45 A bearing bushing 20 is fast in and projects below said upper bracket 16 and carries rotatably disposed therein a sleeve spindle 21 provided between the brackets with a key seat carrying a key 22. Above 50 the upper bracket said spindle is provided with a bearing flange 24 resting on the upper bracket and with a threaded reduced upper end 25 carrying a cup-shaped mold 26 having a lower threaded opening received on said reduced end 25.

A drive pulley 30 is loosely mounted on said bushing 20 and provided with a female clutch cone 31 receiving a male cone 32 provided with a hub 33 slidable on said spindle and provided with an annular 60 clutch groove 35 and with a key-way receiving said key 22, whereby said sleeve spindle is constrained to rotate with the female cone 32.

A yoke lever 36 is fulcrumed on said 65 front web 14 and provided with a handle 37 at its free end, and intermediately with a shift device (not shown) engaging in said groove 35.

A draw rod 40 slidably passing through 70 said sleeve spindle is provided with a nut 41 on its lower end for limiting its upward movement, and has its upper end provided with a convexed lower draw-head 42 slid-
able in said mold.

A cap 43 on said mold is provided with a central opening and with a downwardly and inwardly turned bearing and locking flange 45, the latter engageable with and partly under ball-bearings 46 retained in radial ball-seats 47 in the upper edge of the mold and retained in place by retaining screws 48 (Fig. 3). When the mold is rotated, centrifugal force holds the balls 46 in locking engagement with the inturned 85 lower edge of the flange 45, but releases it as soon as the mold ceases to rotate.

A traveling draw-head 50 engageable in the upper end of the mold and having a lower convexed face is provided with a 90 threaded stem 51 passing through said central opening and receiving a headed sleeve 52 loosely received in a large opening of an exterior threaded cup-socket 55 having its bottom engaging under the head 56 of said sleeve. The head 50, stem 51 and sleeve 52 are provided with an axial vent 57 for the passage of expanding and contracting air during operation of the device. A guide block 58 formed with a central cavity 59 has a threaded lower part receiving said cup-socket and an upwardly extended part 60 having a passage 61 therein.

A pair of vertical supports 62 secured against said side flanges 13, receive and guide therebetween the rear part of said block 58; and guides 63 on the inner face of said supports engage the rear face of said block.

A cylinder 65 resting on said base web 12 between said side flanges 13 having an upper head 66 and lower head 67 receives a piston 68 provided with a piston rod 69 passing out through said upper head 66 and carrying a traveling pulley 70 on its upper end.

A pulley shaft 73 between upper ends of said supports 62 carries a main pulley 74 thereon; and a cable 75 or other flexible means has its lower end knotted as at 76 and passed through said passage 61 and its upper part passed over said main pulley 74, under said traveling pulley 70 and secured 15 to a cross bar 77 fast below said main pulley.

A four-way valve 80 fed by a pressure feed pipe 81 leading thereto directs pressure medium to either of the branch pipes 82 or 83 leading from said valve to opposite ends 20 of the cylinder; and a control rod 84 controls said valve whereby said pressure medium can be at will directed to either end of the cylinder thereby to reciprocate the piston and raise or lower said traveling head 25 50 and block 58. The handle 85 on said control rod is conveniently disposed near and over said handle 37 of the yoke lever.

The operation of the device is very simple. Pressure medium is directed to the upper end of the cylinder thereby raising the upper draw-head 50, and the cap 43 after which the draw-heads 42 and 50, which are of steel, are heated, as by blow torch or hot glass sufficiently to make the glass stick as 35 in Fig. 1. The mold itself is made of cast iron and remains relatively cool so the glass will not stick. A charge 88 of molten glass is then poured into the rotatable mold 26 until the mold is about half full (Fig. 3). 40 By manipulating the handles 85 and 37 the draw-head is then lowered and the cone 32 raised, thereby closing and rotating said mold and locking the cap in place with the charge in the mold; thereby centrifugally 45 to form a glass cylinder 89 (Fig. 4) closed at the lower end 90 open at the upper end 90' and enclosing an air-space 91 therein. Next the cone 32 is lowered, the cylinder thereby brought to rest, and the cap 43 thereby unlocked. Pressure medium is then again directed to the upper part of the cylinder 65, thereby drawing upwardly said heads 50 and 42 and said ends 90 and 90' apart thereby to elongate said cylinder 89 and to reduce 55 its diameter; thereby producing a tube 92 (Fig. 5) with a closed lower end 93. A slight cooling of the tube and the cutting off of its ends then completes the tube.

We claim as our invention:

60 1. In combination, a rotatable mold; a draw head in each end of the mold; and means for moving the draw heads apart.

65 2. In combination, a rotatable mold; a draw head normally in one end of the mold and slidably in the mold; a traveling draw

head rotatably mounted in the other end of the mold; and means for drawing the draw heads apart.

3. In combination, a rotatable sleeve spindle; a mold on the upper end thereof; a rod passing through said spindle; a lower draw spindle; head on the rod and slidably in the mold; a traveling draw head rotatably mounted in the upper end of the mold; and means for raising and lowering the traveling draw head.

4. In combination, a rotatable sleeve spindle; a clutch controlling the rotation of said spindle and comprising a manual shift means; a mold on the upper end thereof; a rod passing through said spindle; a lower draw head on the rod and slidably in the mold; a traveling draw head rotatably mounted in the upper end of the mold; and means for raising and lowering the traveling draw head and comprising a manual control means near said shift means.

5. In combination, a standard; a sleeve spindle rotatably mounted thereon; a drive pulley; a clutch interposed between said pulley and sleeve; a mold mounted on the upper end of the spindle; a draw rod passing through said spindle; a lower draw head on the upper end of said rod and slidably in said mold; a cap rotatably mounted on the upper end of the mold; a traveling draw head mounted on said cap and in the upper end of the mold; supports mounted on said standard; a cylinder on said standard between said supports and having a piston and piston rod; a pulley on said supports; a flexible means passing from said piston rod over said pulley to said cap; and means for directing pressurized medium to either end of the piston.

6. In combination, a standard thereon comprising upper and lower bearing brackets having upper and lower aligned openings; a bearing bushing fast in and projecting below said upper brackets; a sleeve spindle rotatably disposed in said bushing and lower opening and provided between the brackets with a key seat; a key in said seat; a drive pulley loosely mounted on said bushing and provided with a female clutch cone; a male cone received in said female cone and provided with a hub slidable on said spindle and provided with an annular clutch groove and with a key-way receiving said key; a yoke lever fulcrumed on said front web and provided with a handle at its free end, and intermediately with a shift device engaging in said groove; a mold on the upper end of the sleeve spindle; a rod passing through said spindle; a lower draw head on the rod and slidably in the mold; and a traveling draw head in the upper end of the mold.

7. In combination, a rotatable sleeve spindle provided with a threaded reduced upper end; a cup-shaped mold having a lower

- threaded opening received on said reduced end; a draw rod passing through said sleeve spindle and provided with a nut on its lower end; a convex lower draw head on the upper 5 end of the rod and fitting and slideable in said mold; a traveling draw head rotatably mounted in the upper end of the mold; and means for raising and lowering the traveling draw head.
- 10 8. In combination, a rotatable sleeve spindle; a cup-shaped mold mounted on the upper end of said spindle, and having radial bearing seats at its upper edge; a draw rod passing through said sleeve spindle; a convexed lower draw head on the upper end of the rod and slideable in said mold; ball bearings retained in said seats; a cap on said mold and provided with a central opening, and with a downwardly and inwardly turned 15 bearing flange engageable with and locking under said ball bearings; a traveling draw head engageable in the upper end of the mold and having a lower convexed face and provided with a threaded stem passing 20 through said central opening; and means for raising and lowering the cap.
9. In combination, a rotatable sleeve spindle; a mold on the upper end thereof; a rod passing through said spindle; a lower draw 25 head on the rod and slideable in the mold; a traveling draw head engageable in the upper end of the mold and having a lower convexed face and provided with a threaded stem passing through said central opening; 30 a headed sleeve received on said stem; an exteriorly threaded cup-socket having its bottom engaging under the head of said sleeve and provided with a large opening loosely receiving the sleeve; a guide block 35 formed with a central cavity having a
- threaded lower part receiving said cavity, and an upwardly extended part having a passage therein; a pair of vertical supports between which the rear part of said block is received; and flexible means for 40 raising and lowering the traveling draw head and passing through said passage and knotted.
10. In combination, a rotatable spindle; a manual shift lever having a handle for 50 controlling the rotation of said spindle; a mold on the upper end thereof; a lower draw head in the mold; a traveling draw head rotatably mounted in the upper end of the mold; a cylinder having a piston and piston 55 rod; a flexible means passing from said piston rod to said traveling draw head; a four-way valve; a pressure feed pipe leading thereto; branch pipes leading from said valve to opposite ends of the cylinder; a control rod for said valve whereby pressure medium can be directed to either end of the cylinder thereby to reciprocate the piston and raise the lower said traveling head; and a handle on said control rod and disposed over said handle of the shift lever. 60
11. In combination, a mold; a cap rotatably mounted on the upper end of the mold; centrifugally operated means for locking the cap on the mold when the cap and mold are 65 rotated; a travelling draw head attached to said cap and in the upper end of the mold; and means for raising and lowering the cap and travelling draw head. 70
